UNITED STATES PATENT OFFICE.

EDGAR W. ANTHONY, OF BOSTON, MASSACHUSETTS.

DESIGN FOR A HEATING-STOVE.

SPECIFICATION forming part of Design No. 13,324, dated October 3, 1882.

Application filed August 16, 1882. Term of patent 14 years.

To all whom it may concern:

Be it known that I, EDGAR W. ANTHONY, of Boston, in the county of Suffolk and State of Massachusetts, a citizen of the United States, have made a certain new and useful Design for Heating-Stoves, of which the following is a full, clear, and exact description, reference being had to the accompanying plates in describing the same, in which—

10 Plate 1 is a photograph of the complete stove; and Plate 2, a photograph of the top plate and its cover, and of the plate above the ash-pit.

15 The features of the design embrace the stove as a whole and the ornamental portions hereinafter referred to.

20 The shape of the stove-leg A and the character of its ornamentation are very well shown in the photograph, and need not be described more specifically.

25 The shape and ornamentation of the ash-pit door B are also well represented by the photograph, as are also the stove-pillar C, forming the corners of the base portion of the stove and the side panel, D.

30 The shape and ornamentation of the plate F are well represented in Plate 2, and the shape and ornamentation of the frame G about the door to the combustion-chamber and the shape and ornamentation of the said combustion-chamber door H are well shown in Plate 1.

35 The ornamental perforated ring I below the flange of the top-plate K is well shown in Plate 1, and the configuration and ornamentation of said top-plate K and cover L, are shown in Plates 1 and 2.

The shape and ornamentation of the urn M are well illustrated in Plate 1.

40 The sheet-metal barrel N of the stove, its divisions into sections by a plate, O, and its ornamentation by means of horizontal mold-

ings or corrugations, and the proportion which it bears to the lower or base section and top, are all well represented in Plate 1.

Having thus fully described my design, I 45 claim and desire to secure by Letters Patent of the United States—

1. The design for stove-leg, substantially as shown and described.

2. The design B for a door, substantially as 50 shown and described.

3. The design C for a corner of a base-section, substantially as shown and described.

4. The design D for a stove-panel, substantially as shown and described.

5. The design F for a stove-plate, substantially as shown and described.

6. The design G for a door-frame, substantially as shown and described.

7. The design H for a door, substantially as 60 shown and described.

8. The design I for an open-work ring, substantially as shown and described.

9. The design K for top-plate, substantially 65 as shown and described.

10. The design L for a cover, substantially as shown and described.

11. The design M for a stove-urn, substantially as shown and described.

12. The base-section of a stove, shaped and 70 ornamented as shown and described.

13. The design for upper section of a stove, including the top-plate K, cover L, and urn M, substantially as shown and described.

14. The barrel N, the base-section, and the 75 upper section, having the shape and proportions substantially as described.

EDGAR W. ANTHONY.
